FILING CASE**Jean Charles Paul Camus, Paris, France****Application January 23, 1956, Serial No. 560,826****Claims priority, application France January 21, 1955****1 Claim. (Cl. 40—156)**

This invention relates to filing cases and more particularly to a filing case in which documentary material may not only be collected and stored, but also displayed, to which use, however, the invention is not restricted.

An object of the invention is to provide a device for the filing or storing of plans, maps, pictures, photographs and the like which also serves as a frame for displaying the outermost material filed therein. Desirably, the device should be compact in size, light in weight and easily accessible to the user for insertion or withdrawal of documents without the necessity of removing the device from a supporting surface. In addition the combination filing case and display frame must be of simple, sturdy, dependable construction.

I have now invented a case, the features of which embody the above stated objects in providing an improved device for both filing and displaying flat documents. A preferred embodiment of this invention comprises a sturdy box-like frame which may be fabricated to any desired size to meet specific requirements. Movable folding extensions acting as operative molding strips are hinged to one or more sides of the frame structure so that when the extensions are folded inwardly, documents are securely retained within the case and when opened outwardly, access is afforded to the interior of the case for insertion or withdrawal of contents therefrom.

The case may be reinforced by a rigid back which can be secured to or within the frame structure by a second set of folding extensions pivotally attached to the rear portion of the frame.

Other objects, advantages and novel details of construction of this invention will be made more apparent from the following description wherein reference may be had to the accompanying drawings in which:

Fig. 1 is front elevation of a filing case showing the manner in which the extensions may be opened or locked in closed position to retain and frame material stored therein; and

Fig. 2 is a rear perspective view of a storage case such as is illustrated in Fig. 1 showing a rigid backing sheet retained by a second set of retaining extensions.

Referring to the drawings, Figs. 1 and 2 show a receptacle or storage case 12, having a body of open frame construction composed of four side portions 11, 12, 13 and 14 of optional dimensions, here shown miter joined in the usual manner. The front of the case is designated 15 and the rear 16.

The case is closed by a series of inwardly folding extensions 18 several of which may be pivotally attached to the sides of the body portion as by hinges 17. It may be preferable to have the lower extension integral with the case. The extensions when closed form moulding strips for the frame, the ends of which are cut for lap joint mating engagement usually at the corners, though center joining may be preferable in some instances. This

2

construction not only provides a flush surface on the front of the case to form an attractive frame for stored material, but the extensions are arranged to interlock like shutters so that the side extensions overlie the bottom extension, and the top extension overlies the side extensions to provide the retaining moulding when in closed position.

Advantageously, the rear or opposite side of the case can be arranged so that the extensions lock in a vertical or upright position thus affording appropriate framing for both horizontal and vertical pictures by merely reversing the frame.

If a square-jointed frame (not shown) is used for the case, the corners or retaining strips 18 are cut for straight overlap joining in the same manner as in the mitered frame illustrated.

Extensions 18 may be hinged to the outer edges of the body portion to obtain varied desired effects, but in this instance wide extensions overlying the side portions must necessarily be used in order to form a retaining edge for the documentary, pictorial and other flat material stored in the case.

It may in some instances be preferable to use two right-angled extensions to close the case, each such extension being pivotally attached to the frame along one side thereof.

A sheet of transparent material can be optionally retained in the face and/or rear of the case for protection and inspection of displayed material.

As stated above, the rear of the filing case 16 may be similarly constructed to the face 15 with operable extensions 18, so that material may be inserted and displayed from both the front and rear of the case. However, it may be preferred to reinforce the frame by a rigid back cover 19. In this instance, apertures 22, 22 may be made in the back cover through which the contents can be pushed forward toward the open face portion 15 in order to remove selected material without defacing it. The cover may be removably positioned inside the case as shown in Fig. 2, be fixedly or releasably attached to the rear of the case as desired.

The corners of the extensions 18 are accurately fitted so that when closed, they remain in frictional interlocked engagement. However, additional securing means 23 could be used if required.

In operation, the controlling or uppermost extension 18 is unfolded from its closed position to release one or more side strips for access to the filing case. If advantageously hung upon a wall or other appropriate surface, access may be had without removing the case from the support.

The forms of the invention here described and illustrated are presented merely as examples of how the invention may be embodied and applied. Other forms, embodiments and applications of the invention, coming within the proper scope of the appended claim, will, of course, suggest themselves to those skilled in the art.

I claim:

60 A case for storing stiff, flat material comprising a box, one side of said box having an open frame, extensions pivotally attached to said frame adapted to fold inwardly thereof to enclose said material and provide moulding for said frame to display the foremost material therein, said moulding extending inwardly from and forming a part of one side of said frame, the outer surface of one of said extensions being mitered at both corners to form an inner triangular portion, extensions projecting inwardly from and forming a part of the sides adjoining the first mentioned side of said frame, the inner surface of said second mentioned extensions being mitered

at one end to form outer triangular portions for mating engagement with said inner triangular portions, the outer surface at the opposite end of said second mentioned extensions being mitered to form inner triangular portions, and an extension projecting inwardly from and forming a part of the remaining side of said frame being mitered on the inner surface of each corner to form outer triangular portions for mating engagement with said inner triangular portions on said adjoining extensions.
